C. J. HEMMERT

ILLUMINATED LICENSE NUMBER FOR AUTOMOBILES

Filed March 7, 1922

Fig. 5.

Inventor
C. J. HEMMERT

ପତ୍ର

John S. Dobbie

UNITED STATES PATENT OFFICE.

CHRISTIAN J. HEMMERT, OF WAPAKONETA, OHIO.

ILLUMINATED LICENSE NUMBER FOR AUTOMOBILES.

Application filed March 7, 1922. Serial No. 541,694.

To all whom it may concern:

Be it known that I, CHRISTIAN J. HEMMERT, a citizen of the United States, residing at Wapakoneta, in the county of Auglaize 5 and State of Ohio, have invented certain new and useful Improvements in Illuminated License Numbers for Automobiles, of which the following is a specification.

This invention relates to an illuminated 10 license number for automobiles, and has for its primary object to provide a simple and economical form of casing for supporting the license number and for illuminating the same in order that the number will be clearly 15 displayed, and especially at night.

With the foregoing and other objects in view that will appear as the nature of my invention is better understood, the same 20 consists in the novel features of construction, combination and arrangement of parts illustrated in the accompanying drawings and more particularly pointed out in the appended claim.

In the accompanying drawings, which are 25 for illustrative purposes only and are therefore not drawn to scale:—

Figure 1 is a side elevation of the illuminated number for automobiles.

Figure 2 is a transverse sectional view of 30 the same applied.

Figure 3 is a longitudinal sectional view of the same.

Figure 4 is an elevational view of the modified form with parts broken away.

Figure 5 is a transverse sectional view of the form of the invention as shown in Figure 4.

Referring to the drawings for a more particular description of my invention and in 40 which drawings like parts are designated by like reference characters throughout the several views, the numeral 2 represents my illuminated license number plate, as a whole, which may be supported on one of the rear 45 fenders 3 of the automobile by the brackets 4 and 5 or other equivalent means or which may be mounted at the front of an automobile. In fact, a license number plate may be arranged at both the front and rear of the 50 machine if desired, and may be supported in any suitable position.

As shown in the drawings, my invention

comprises a preferably hollow rectangular oblong frame 6, formed along its front edge or face with a continuous channel or recess 55 7 in which is arranged a continuous strip 8 of felt or other cushioning material against which the edges of the colored glass plate or panel 9 rest. A corresponding plate 10 of metal or other suitable material is positioned over the transparent plate 9 with its outer face preferably flush with the front edge of the frame 7. This plate 10 bears the license number, which is cut or stenciled therein and is held in removable position together with the transparent colored panel 9 by the hollow rectangular angle frame 11 which is fitted over the front edge of the frame 6 with one member, as 12, engaging the outer edges of the latter and its other member, as 13, fitting over the front edge of said frame 6 and the front face and edges of the plate 10. The frame 11 is held in removable position by the fastening screws 14 or other equivalent means, which are preferably arranged 60 65 at the corners thereof and screw into the front face of the frame 6. The back of the frame 6 is closed or covered by the metal cover 15 formed at its top, bottom and end edges with a continuous inwardly projecting flange 16 which extends and fits over the outer edges of the casing 6. A light bulb 17 extends into the space 18 between the transparent colored panel 9 and the cover 15, preferably through the top of the 70 75 frame 6 and is adapted to illuminate the license number. Current is supplied to the electric bulb by the circuit wires 19 and 20 which lead to a battery or other source of electrical energy.

The flanges 13 are integral with the flanges 16 and the cover 15.

In the modified form of my invention a transparent colored panel 9 as well as a metal plate 10 bearing the license number, 80 is arranged at the back as well as the front of the casing 6 in order that the license number of the car will be visible from either the front or rear. In this form of my invention, the cover 15 is dispensed with and 85 a frame similar to the frame 11 employed, as will be apparent.

With the use of my invention, the license number plate will be illuminated and hence

clearly visible at all times and especially at night with the result that reckless driving and accidents will be greatly reduced for the reason that the identity of the offender 5 may be easily established.

It will be understood that the parts may be of any desired dimensions and made of any material or materials found best adapted in actual practice.

10 From the foregoing description taken in connection with the drawings, it is thought that the construction, operation and advantages of my invention will be readily understood without requiring a more extended 15 explanation.

Various changes in the form, proportions and minor details of construction may be resorted to without departing from the principle or sacrificing any of the advantages 20 of my invention as defined in the appended claim.

Having described my invention, what I claim as new and desire to secure by Letters Patent, is:—

An illuminated license number plate holder comprising a rectangular frame which is recessed at its edges, a transparent panel and a stencilled plate fitting at their edge portions in the recess, a cover member for the back, top, bottom and ends of the frame and having flanges covering the front edges of the frame and of the plate and holding the latter and the panel in the recess, the intermediate body portion of the cover member and the panel and plate lying in parallel planes and an electric bulb located in the upper portion of the frame between the cover and the transparent panel and at a point above the stenciling in the plate. 25 30 35

In testimony whereof I affix my signature.

CHRISTIAN J. HEMMERT.
